UNITED STATES PATENT OFFICE.

JOSEPH H. STANNARD, SR., OF COLUMBIA, SOUTH CAROLINA.

BOILER-FURNACE.

1,395,610.

Specification of Letters Patent.

Patented Nov. 1, 1921.

Application filed October 7, 1919. Serial No. 329,150.

To all whom it may concern:

Be it known that I, JOSEPH H. STANNARD, Sr., a citizen of the United States, residing at Columbia, in the county of Richland and 5 State of South Carolina, have invented new and useful Improvements in Boiler-Furnaces, of which the following is a specification.

The present invention relates to improvements in boiler furnaces and more especially 10 to the fire box of such a boiler.

The particular object of the invention is to provide within the fire box of a steam 15 boiler an arch which will act to properly direct the products of combustion along the crown sheet and uniformly distribute them to all of the boiler flues.

A further object of the invention is to provide means whereby a maximum sized 20 grate may be employed and all parts thereof utilized.

With the constructions heretofore proposed it has been impossible to use a grate 25 extending continuously from the rear flue sheet of the boiler to the rear end of the fire box and have the products of combustion uniformly distributed to all of the flues.

While the invention may be advantageously employed with any horizontal steam 30 boiler it is particularly adapted for locomotive boilers and is therefore illustrated in the accompanying drawings in connection with such a boiler.

In the drawings Figure 1, is a vertical 35 sectional view through a locomotive boiler having one embodiment of the present invention applied thereto.

Figs. 2 and 3 are sectional views of the 40 fire box, showing slightly modified forms of the invention.

Referring to the drawings, 1 designates the water space or chamber of the boiler through which extend the usual flues 2, the 45 ends of which are supported in front and rear flue sheets 3, 4. The rear flue sheet is extended downward below the body of the boiler 1, to provide part of a water leg 5, and at its rear end the body of the boiler 50 is caused to extend across the rear end of the fire box, admission to which is through apertures 6, 7, that are closed by suitable doors not illustrated.

The parts of the boiler before referred to 55 may be of any suitable construction, the

particular form conventionally illustrated being what may be considered a standard type.

Tubes 8 connect the water leg 5 with the water chamber at the rear end of the fire 60 box, such tubes being inclined upwardly from their forward to their rear ends. It is customary to support on such tubes an arch of refractory material which extends from one side wall of the fire box to the other 65 end generally parallel to the tubes 8. Practical experience with such a construction shows that as the draft through the lower tiers of tubes or flues is stronger than that through the upper series the products of 70 combustion rising from the grate and passing over the rear end of said arch are caused to be drawn downwardly through the lower series of flues and the uppermost tubes receive little if any direct heat therefrom. 75

By the present invention the arch supported by the tubes 8, is provided with an upwardly projecting portion 9, the upper surface of which, as shown in Fig. 1, is flat or parallel with the crown sheet of the fire 80 box. Preferably said upward projecting portion is made of substantially triangular form in longitudinal section, the forward end thereof extending parallel with the rear flue sheet and being spaced therefrom sufficiently to afford room for a workman to inspect, and if necessary repair, the connection between such sheet and the boiler flues. The space between the top of the portion 9 of the arch and the crown sheet of 85 the fire box is sufficient to permit a workman to enter the combustion chamber immediately in rear of the flue sheet 4. As shown in Fig. 1, the arch referred to includes a portion 10, extending parallel with the tubes 90 8, and which may, as shown, be separated slightly from the rear flue sheet to provide a passage 11, for flame rising from the grate or in some instances said section 10, may extend continuously to said flue sheet. 95

It has been practically demonstrated that with an arch of the form and relative proportions shown the products of combustion rising from the grate will be uniformly distributed to all of the tubes or flues and it 100 will be seen that such structure provides for maintaining the products of combustion in contact with the crown sheet of the fire box throughout its length. This results in obtaining the maximum heating efficiency from 105 110

the fire. In the embodiment of the invention illustrated in Fig. 2, the upwardly extending portion of the arch has the top surface of the forward portion 12 thereof, inclined 5 downward slightly from the top of the rear portion 13, but the relation of the forward end thereof to the rear flue sheet is substantially the same as in Fig. 1.

Instead of making the arch of refractory 10 material as before described and illustrated in Figs. 1 and 2 it may be formed as a part of the water chamber of the boiler. In this construction, which is shown in Fig. 3, the portion 14 of the water chamber is projected 15 over the grate in the fire box and communicates with the body of the boiler through the side walls of the fire box and also through an opening 15 in the rear flue sheet. The top of such chamber 14, like the upper sur- 20 face of the portion 9, of the arch shown in Fig. 1 causes the products of combustion to travel along the crown sheet throughout the length thereof and the wall 16 of the water chamber 14 is so related to the rear flue sheet 25 that said products of combustion are uniformly distributed to all of the flues.

It will be understood that the distance separating the abutment or upward projection of the arch from the rear flue sheet will 30 be accurately determined by the strength of the draft which is to be induced through the several flues prior to building the arch in the fire box. The amount of draft in the invention illustrated is controlled by an ad- 35 justable damper 17, arranged within the smoke box at the forward end of the boiler, a suitable perforated baffle 18 being pro- vided in the rear portion of said box in front 40 of the upper series of tubes or flues and a screen 20 being provided for preventing cinders and the like from escaping from the smoke box.

It will be seen that the present invention 45 enables use to be made of a grate of maximum size as it can extend completely from the rear flue sheet 4, to the rear wall of the fire box and that the baffle or means for controlling the passage of products of combustion to the flues does not obstruct or cut 50 off any portion of the grate surface. Further it is possible to admit flame to the combustion chamber between the upwardly ex- tending portion of the arch and the rear flue sheet so as to insure perfect combustion 55 of the gases therein and the products of combustion are uniformly distributed over

the entire rear face of the rear flue sheet and to all of the tubes opening therethrough.

Having thus described the invention what is claimed is:

1. In a horizontal fire tube boiler, includ- 60 ing a fire box provided with a grate, a crown sheet and a substantially vertical tube sheet, an arch extending from side to side of the fire box above the grate with its lower 65 surface inclined longitudinally and its upper surface separated from the crown sheet by a passage of substantially uniform height throughout the length of the arch and ex- tending to within a short distance of the 70 tube sheet, said arch being provided with means for preventing direct passage of products of combustion from most of the grate area to the tubes opening through the lower section of the tube sheet.

2. In a horizontal fire tube boiler, includ- 75 ing a fire box provided with a grate, a crown sheet and a substantially vertical tube sheet, an arch extending across the fire box above the grate, throughout the greater portion of 80 the length thereof and having, adjacent the tube sheet, an imperforate surface extending substantially parallel to and at a rela- tively slight distance from said tube sheet across the adjacent ends of the tubes in ap- proximately the lower half of the boiler, whereby the products of combustion are 85 caused to travel throughout the length of the arch in planes above the level of the lower half of the series of fire tubes, for the 90 purpose described.

3. In a horizontal fire tube boiler, includ- 95 ing a fire box provided with a grate, a crown sheet and a substantially vertical tube sheet, an arch extending from side to side of the fire box and throughout the greater part of the length thereof, said arch including an upwardly projecting portion, substantially triangular in longitudinal sec- 100 tion with its vertical portion extending to approximately above the level of the lower half of the series of fire tubes and spaced from and parallel to the tube sheet, for the purpose described.

In testimony whereof I have hereunto set 105 my hand in presence of two subscribing wit- nesses.

JOSEPH H. STANNARD, SR.
